5 Claims. (Cl. 103—163)

This invention relates to piston pumps or motors with means for varying the stroke of the piston and particularly to machines of this kind in which the cylinder chambers are formed by a frame sliding in one direction in a hollow body and in which another frame slides in a direction at right angles to the first, a circular movement of translation being imparted to this latter frame relatively to the hollow body through an eccentric. Said arrangement allows the outlet or inlet of the fluid from or to the cylinder chambers directly through the hollow eccentric and the sliding frames.

According to the present invention, the rotary movement of the sliding frames is avoided by the fact that the eccentric controlling the inner sliding frame consists of a spherical head connected to a rotating and pivoting shaft which is rotatably mounted in a spherical bearing located at some distance from said head; a conical movement is imparted to said shaft around the center of said bearing and the angle of this conical movement can be varied at will.

Another feature of the invention consists in that in said shaft and in its spherical head are provided ducts and ports for the flow of the fluid which ports cooperate with ports provided in a spherical cavity of the inner sliding frame so as to ensure delivery, whatever may be the angle of the conical motion of said shaft.

A further feature of the invention consists in that the sliding frames each carry a pair of opposite pistons, the pistons carried by the inner frame are at right angles to the two carried by the outer frame and slide within cylinders which are also carried by the outer sliding frame, and the pistons carried by the latter slide within stationary cylinders connected to the outer body. Said frames do not act as pistons, but merely carry the same, they can therefore have large dimensions which are larger than the diameter of the pistons, thus a spherical head of large diameter to be used in the inner frame, which is an advantageous condition for reducing the wear of the friction surfaces and for maintaining the fluid-tightness required for the delivery of the fluid through the ports provided in said friction surfaces.

The annexed drawings illustrate, by way of example, an embodiment of a pump according to the invention.

Fig. 1 is a vertical longitudinal section of the whole of said pump, the pump shaft being at dead center (no delivery).

55 Figs. 2 and 3 are respectively a vertical section

according to line II—II of Fig. 1, and a partial horizontal section of the drive for the pump shaft.

Fig. 4 is an elevation, partly in section, of the pump shaft.

Fig. 5 is a cross section made according to line V—V of Fig. 1.

This pump comprises two rectangular frames 10 and 11 sliding the one in the other in the direction ZZ (Fig. 5) and an outer body 7 in which said outer frame 11 slides in the direction YY perpendicular to ZZ.

The frame 10 comprises two symmetrical halves 10a, 10b and carries two cylindrical projections 10c, 10d about which are secured sleeves 15 10e, 10f forming pistons, which slide in two cylinders 11e, 11f connected to the frame 11. The latter also carries two projections 11c, 11d surrounded by sleeves 11g, 11h forming pistons and sliding in cylinders 1e, 1f connected to the body 7.

Said body is also composed of two symmetrical parts 7a, 7b and the latter are mounted within a casing 6.

The inner frame 10 is provided with a spherical cavity 10g in which is loosely fitted the spherical head 5a of a driving shaft 5. Between its ends, said shaft carries a ring 16a (Fig. 1) maintained by rollers 16 at the middle of a spherical bearing 16b secured to casing 6, so that said shaft can rotate about its own axis and revolve around an axis XX passing through the center 0 of the bearing 16b.

When the shaft 5 is inclined according to a certain angle (towards the positions α or α' indicated in dot and dash lines) relatively to the axis XX, the same describes a conical movement about XX and its head 5a imparts to frame 10 a circular movement of translation so that frame 10 moves to and fro in frame 11 and the latter moves to and fro in the body 7.

During oscillation of shaft 5, the head 5a tends to describe an arc of circle about the center of the spherical bearing 16b, so that this head moves transversely to the plane of the frames and moves these latter in this direction. But the stroke of the pistons is so small that said theoretical transverse displacement is nearly null (a few hundredths of a millimeter in the drawing) and is absorbed by the unavoidable plays between the bearing 16b and the bearing 16a, between the head 5a and the frame 10, between this frame and frame 11, and between the frame 11 and the body 7 in the direction of the axis of the pump;

the operation of the pistons is therefore not influenced by the oscillation of shaft 5.

The shaft 5 is actuated by a driving shaft 1 mounted in a casing 4, 4a connected to casing 6, and its axis is in alignment with the axis XX. The inner end of the shaft 1 forms a sleeve 22 within which extends the end 26a of shaft 5 and which is sufficiently large for allowing said shaft to oscillate according to any desired angle about the center 0.

The end 26a is fork-shaped and carries, by means of an axle 24, a disc 23 located in said fork and guided at two diametrically opposed points in mortices 22a, 22b of the sleeve 22.

The periphery of disc 23 is partly toothed and these teeth 23a mesh with a rack 25 connected to a sleeve 19 slidably mounted on sleeve 22. The axle 24 is provided out of the center of the disc 23, so that the rotation of the latter has the effect of shifting shaft 5 relatively to the axis XX and of modifying the angle of the cone described by said shaft, and, consequently of modifying the stroke of frames 10, 11.

The longitudinal displacement of sleeve 19 is obtained by means of a hand lever 27 pivoted at 28 on the casing 4 and of a sleeve 18 sliding within the latter, the inner end 21a of lever 27 engages a recess 18a of sleeve 18 and the latter is connected to the sleeve 19 through a ball bearing 20 and a ball thrust bearing 21.

In the embodiment shown by way of example 30 the lever 27 is connected to an accelerating pedal 46 through a link made of two telescopic parts 41a, 41b, a pressure spring 48 checking the extension of said telescopic parts.

The casings 4 and 6 contain a liquid, such as 35 oil, and during normal operation of the pump, said liquid is sucked by the pistons of frames 10 and 11 through ports 5f, a duct 5b and a port 5d provided in shaft 5, said port opening on one side of the spherical head 5a, (Fig. 4); said liquid 40 is forced by the same pistons through a port 5e and a duct 5c provided in said head 5a, said port 5e being diametrically opposed to said port 5d.

Said ports cooperate with ports 10h, 10i and 11i, 11j provided in the frames (Fig. 5) so as to 45 connect port 5d with the cylinders 11e, 11f, 7e, 7f at the time the capacity of said cylinders increases, and to connect said cylinders with port 5e at the time their capacity decreases. The liquid is thus forced through the duct 5c of shaft 50 5 when said shaft is inclined towards the position α (Fig. 1).

The direction of flow of the pumped liquid is inverted when the disc 23 is turned so as to incline shaft 5 towards the position α' ; the liquid 55 would then be sucked at 5c and delivered at 5f.

In the example given herein, the casing 6 is closed on the side of head 5a by a cheek member 15 at the middle of which can slide a sleeve 56; beyond said cheek member is secured the casing 6a of a hydraulic motor (not shown) the exhaust port of which is connected to the interior of casing 4 by means permitting the liquid to circulate in a closed circuit.

A spring 57, arranged in a recess 58 and pressed 65 between a stationary ring 59 and the sleeve 56, presses the latter towards the pump. Said sleeve thus bears against a ring 60 secured to the frame 10, the contact surfaces of the said sleeve and of the said ring being faced so as to slide one against 70 the other.

Resistance to delivery produces upon the piston-frames reactions which tend to bring back the center of head 5a towards the axis XX and, consequently, to bring back the disc 23 and its driving mechanism to dead center. In order to bal-

5
ance, at least partly, the recoil action upon the driving mechanism independently of the thrust exerted by the hand of the driver upon lever 27 or by his foot upon pedal 46, the following device has been provided:

The sleeve 56 is in communication, through holes 59a, with ducts 61 (only one of said holes being shown in Fig. 1) which lead into cylindrical chambers 41 provided in the end of the casing 4, 4a, so that the delivery pressure will act 10 upon pistons 43 sliding in said chambers and longitudinally pushing the ball thrust bearing 21.

The said thrust, transmitted through sleeve 19 and rack 25 to disc 23, tends to cause the latter to rotate in a direction reverse to the force exerted by shaft 5 under the influence of the resistance to delivery and, consequently, tends to balance, at least partly, said force upon the disc 23 and upon its driving mechanism.

It is to be observed that, due to the yielding connection 47a, 47b, 48 between lever 27 and pedal 46, the inclination of the shaft 5 can be controlled as well by the foot as by the hand; the tension of the spring 48 can be advantageously adjusted so that the displacement of the accelerating pedal 25 under the pressure of the foot will be transmitted to the lever 27 and to the sleeve 18 in a suitable ratio so that the variation of stroke or motion resulting from the said displacement will be substantially proportional to said power without 30 causing the speed of the engine to vary.

Moreover, should the resistance to delivery vary for a given inclination of the shaft 5, the reaction upon the regulating device, partly balanced by virtue of the action of the pistons 43, 35 will be absorbed by the spring 48, so that, the pedal 46 being left motionless, the lever 27 will be displaced by the action of the said spring and will automatically modify the stroke of the pistons, consequently the delivery, without changing 40 in a noticeable manner the speed of rotation.

The machine illustrated further comprises a device allowing one to divert the delivery of the pump through a by-pass; for that purpose, between the recess 58 around the sleeve 56 and a 45 recess 65 in the cheek member 15, a valve chamber 66 is provided in the said cheek member 15, said chamber communicating with these two recesses through ducts 66a, 66b. Under normal conditions, the communication is cut off by a 50 valve 67. In the example illustrated, the tail of said valve is made of two telescopic elements 67a, 67b embracing a joint 68. The pressure required for ensuring the fluid-tightness of said joint is obtained by screwing a threaded tie-rod 69 connecting together the two parts 67a—67b.

The tail 67a, 67b, is screwed at 67c into the cheek member 15 so that by causing the same to rotate, this causes valve 67 to open and, consequently, the pump is short-circuited through 56, 60 58, 66a, 66b, 65, through the interior of the casing 6 which communicates with 65 outside the frame 11, and through the interior of the casing 4 which is in communication with 6 through bearing 16b; or again the normal operation of the 65 pump is reestablished by closing the valve 67.

We claim:

1. A piston machine comprising two frames sliding the one in the other, an outer hollow body in which the outer frame slides transversely to the direction in which the two frames are respectively sliding, a stationary spherical bearing, a pivoting shaft journalled in said spherical bearing and provided at one end with a spherical head journalled in the inner frame, a driving 75

- shaft arranged for rotating about an axis passing through the center of said spherical bearing, and means for varying the inclination of said pivoting shaft relatively to the driving shaft, means 5 for connecting together said shafts for causing them to revolve together about the axis of the driving shaft, said pivoting shaft and its spherical head having inlet and outlet channels provided therein and the inner frame having ports 10 provided therein and arranged for cooperating with the channels of said pivoting shaft for the passage of the fluid entering into and issuing from the variable chambers formed between said sliding frames and between said outer frame and 15 said outer hollow body.
2. A piston machine comprising two frames sliding the one in the other, and an outer hollow body in which the outer frame slides transversely relatively to the direction in which the two 20 frames slide respectively, a stationary spherical bearing, a pivoting shaft journalled in said spherical bearing and provided at one end with a spherical head journalled in the inner frame, a driving shaft arranged for rotating about an 25 axis passing through the center of said spherical bearing, a disc revolving about an eccentric pivot connected to the other end of said pivoting shaft and at right angles relatively to the axis of said shaft, said driving shaft being provided with a 30 recess in which the said disc is guided so as to be able to transmit to the pivoting shaft the rotary motion of the driving shaft and means for causing said disc to revolve about its eccentric pivot for the purpose of modifying the inclination of 35 said pivoting shaft relatively to the driving shaft, said pivoting shaft and its spherical head having inlet and outlet channels provided therein and the inner frame having ports provided therein and arranged for cooperating with the channels 40 of said pivoting shaft for the passage of the fluid entering into and issuing from the variable chambers formed between said sliding frames and between said outer frame and said hollow body.
- 45 3. A piston machine comprising a stationary outer hollow body, in which are provided two cylinders concentric to a common axis and two cylindrical guide-faces between said cylinders and concentric to them, an outer frame provided on 50 two opposite sides with projections in which is provided a cylindrical bore and the ends of which form cylindrical guide-faces arranged to fit in and to slide between the guide-faces of said hollow body, said frame bearing on the two other 55 sides, pistons extending outwardly and arranged to slide in the cylindrical cavities of said hollow body the inner surface of these sides being shaped to form cylindrical guide-surfaces, concentric with said projections, an inner frame bearing on 60 two opposite sides, pistons arranged for sliding in said bores of said projections of the outer frame, the other sides of said inner frame being shaped and arranged to fit in and to slide between said guide-surfaces of the outer frame; said inner frame having provided therein a spherical cavity, a pivoting shaft having a spherical head fitted in said spherical cavity, a stationary spherical bearing in which is located said pivoting shaft, driving means arranged for rotating said pivoting shaft and control means arranged for varying the inclination of said pivoting shaft, said pivoting shaft and its head having inlet and outlet channels provided therein and the inner frame having ports provided therein and arranged for 10 cooperating with the channels of said pivoting shaft for the passage of the fluid entering into and issuing from the variable chambers formed between said sliding frames and between said outer frame and said outer hollow body. 15
4. A piston machine comprising two frames sliding the one in the other, an outer hollow body in which the outer frame slides transversely to the direction in which the two frames are respectively sliding, a stationary spherical bearing, 20 a pivoting shaft journalled in said spherical bearing and provided at one end with a spherical head fitted in the inner frame, means for causing said shaft to rotate about its own axis and to revolve about a stationary axis passing through 25 the center of said spherical bearing and control means for varying the inclination of said pivoting shaft relatively to said stationary axis, yielding elements in said means for partially balancing the thrust due to the reactions of the fluid 30 between said piston frames, said pivoting shaft having inlet and outlet channels provided therein and the inner frame having ports provided therein and arranged for cooperating with the channels of said pivoting shaft for the passage of 35 the fluid entering into and issuing from the variable chambers formed between said sliding frames and between said outer frame and said outer hollow body. 40
5. A piston machine comprising two frames sliding the one in the other, an outer hollow body in which the outer frame slides transversely to the direction in which the two frames are respectively sliding, a stationary spherical bearing, 45 a pivoting shaft journalled in said spherical bearing and provided at one end with a spherical head fitted in the inner frame, control means for varying the inclination of said pivoting shaft and balancing means for partially balancing the thrust due to the reactions of the fluid between 50 said piston frames, said balancing means comprising cylinders and pistons submitted to the pressure of the delivered fluid, said pivoting shaft and its spherical head having inlet and outlet channels provided therein and the inner 55 frame having ports provided therein and arranged for cooperating with the channels of said pivoting shaft for the passage of the fluid entering into and issuing from the variable chambers formed between said sliding frames and between 60 said outer frame and said outer hollow body.
